UNITED STATES PATENT OFFICE.

JOHN VENGE, OF MILWAUKEE, WISCONSIN.

ELECTRIC GENERATING DEVICE FOR RAILWAY-TRAINS.

1,089,995.

Specification of Letters Patent. Patented Mar. 19, 1914.

Application filed January 10, 1913. Serial No. 741,296.

To all whom it may concern:

Be it known that I, JOHN VENGE, a subject of the Czar of Russia, residing at Milwaukee, in the county of Milwaukee and State of Wisconsin, have invented new and useful Improvements in Electric Generating Devices for Railway-Trains, of which the following is a specification.

My invention relates broadly to an improved electric generating system for railway trains, and most specifically to an improved operating means therefor.

An object of my invention is to provide sufficient means for operating an electric generator and consequently providing electric energy for lighting electric lamps throughout the entire train.

Another object of my invention is to provide, in combination with a locomotive, an electric generating system, and automatic means for controlling the operation of said system.

A further object of my invention is to provide an electric generating system the operation of which may be controlled by the engineer at his post of duty but comprising a subordinate controlling device for automatically rendering the generator inoperative.

A still further object of the present invention is in the production of a device of this character which consists of but a few simple parts whereby it may be manufactured and placed upon the market at a minimum cost.

With the above and other objects in view my invention relates to such details of construction and in the arrangement and combination of parts as will be hereinafter fully described and specifically pointed out in the appended claims.

In describing my invention in detail reference will be had to the accompanying drawings wherein like characters denote like corresponding parts through the several views and in which:

Figure 1, is a side elevation of my invention however parts are shown broken away, the entire device being disposed upon an ordinary locomotive. Fig. 2, is a longitudinal sectional view of the automatic controlling means for the generating system. Fig. 3, is a diagrammatic view of the electric circuit as used in connection with the generating system.

In the accompanying drawings wherein is illustrated the preferred form of my invention the numeral 10 designates the body portion or supporting structure upon which the boiler 11 fire box and cab 13 of the locomotive are supported. The body portion is supported through the medium of transverse axles 14 carrying wheels 15 at their respective extremities, the latter traveling upon rails 16 as is clearly shown.

While the above form of locomotive is merely shown for sake of illustrating the attachment of my invention, it is to be appreciated that the same may be eliminated and my invention used upon other forms if occasion should require.

Mounted upon the body portion 10 of the locomotive and preferably near one side thereof is a casing 17, the latter serving as a housing for the electric generator and the means for supporting the same.

The generator is shown in the drawing disposed within the casing 17 and designated by the numeral 18. The ordinary form of generator is shown, as will be recognized it comprising an operating shaft 19 and carrying a commutator 20. The commutator has brushes 21 in contact therewith and on opposite sides thereof, the latter having engagement with electric conductors 22 and 23. The shaft 19 is extended, and has disposed thereon turbine casing 24, the shaft within the casing having suitable blades mounted thereon upon which an expansive fluid is projected. Beyond the casing 24, the shaft 19 has a bevel gear wheel 25, fastened thereon, the latter being in mesh with a second gear wheel 26 carried upon a vertically disposed shaft 27.

A tubular casing 28 is supported by the casing 17, the smaller casing having an annular flange 29 disposed at an intermediate portion therein as is clearly shown. The casing 28 supports the vertically extending shaft 27, this shaft also extending above the top of the casing and carrying a collar 30 near its upper extremity as is clearly shown. Fingers 31 extend from the collar 30 and carry weights 32 at their lower ends for purpose of providing a centrifugal governor. The weights 32 have attached thereto links 33 the latter having engagement with ears 34 carried upon a sleeve 35, which extends within the casing 28 and below the flange 29. For the purpose that will be readily ob-

vious a head portion 36 is provided upon the lower end of the sleeve 35, it being attached thereto by any suitable means.

It will now be recognized that when the 5 shaft 19 is revolved at a high rate of speed, a rotary motion will be transmitted to the shaft 27 consequently rotating the weights 32. As the speed of the shaft 19 increases, the weights will tend to move outwardly, 10 this being due to centrifugal force whereby the sleeve 35 will be raised, as will the head portion 36, and engage the flange 29 so as to prevent the passage of a propelling medium through the casing 28.

15 A pipe 37 connects the upper portion of the casing 28 with the boiler of the locomotive, the passage through this pipe being controlled by a valve 38. A second pipe connects the lower portion of the casing 28 and 20 the upper part of the casing 24, this pipe being designated by the numeral 39. It will now be appreciated, that when steam is admitted from the pipe 37 to the casing 28 it will flow past the head portion 36 through 25 the pipe 39 to the turbine. The steam being projected upon the blades of the turbine consequently rotating the shaft 19 and armature within the generator so that an electric current will be generated through the brushes 30 21 and flow through the conductors 22 and 23 to a switch box 40 in the cab of the locomotive. From the turbine, the steam is exhausted through a pipe 41 and may be used for any suitable purpose. If the shaft 19 is 35 now rotated at a speed which will generate a voltage within the generator greater than the capacity of the electrical circuit, the weights 32 will be thrown outwardly due to centrifugal force and consequently cut off 40 the supply of steam to the turbine.

Electrical conductors to the other coaches of the train may be connected to the switch box 40, this being left to discretion of the manufacturer.

45 From the foregoing it is thought that the advantages and now the features of my invention will be readily appreciated.

I desire to be understood that I may make changes in the construction and in the arrangement and combination of parts without departing from the spirit of my invention.

tion, provided however, such changes fall within the scope of the subjoined claims.

Having thus fully described my invention what I claim as new and desire to secure by 55 Letters Patent is:

1. In a device of the character described a fluid motor, a valve housing provided with an internal-valve seat, a supply pipe communicating with one end of said valve housing, a pipe leading from said fluid motor to the opposite-end portion of said valve housing, a sleeve slidably mounted in said housing and provided with a valve head adjacent its inner end for engaging said valve 65 seat, a shaft extending through said housing and through said sleeve, a centrifugal governor carried by the upper-end portion of said shaft and engaging the upper-end portion of said sleeve to draw said valve 70 head into engagement with said valve seat when said governor is actuated, and means for transmitting rotary motion from the shaft of said fluid motor to the shaft carrying said governor. 75

2. A device of the character described comprising a motor, a supply for said motor, a valve positioned intermediate the length of said supply, a shaft extending through said valve, a governor carried by 80 said shaft and engaging said valve to close said valve when said shaft is rotating at too high a speed, and means for transmitting rotary motion from the shaft of said motor to said governor-carrying shaft. 85

3. A device of the character described, a casing, a motor in said casing, a supply pipe communicating with said motor, a valve housing positioned intermediate the length of said pipe and supported by said 90 casing, a valve in said housing, a shaft extending through said housing and valve, a governor carried by said shaft and connected with said valve to close said valve when said shaft is rotating at too high a speed, 95 and means for transmitting rotary motion from said motor to said shaft.

JOHN VENGE.
